W. C. WHEELER
DEVICE FOR MAINTAINING UNIFORM CONTACT AND PRESSURE BETWEEN
A STATIONARY AND REVOLVING BODY FOR ELECTRICAL MACHINES
Filed June 27, 1924

Fig. 1.

UNITED STATES PATENT OFFICE.

WILLIAM C. WHEELER, OF CHICAGO, ILLINOIS.

DEVICE FOR MAINTAINING UNIFORM CONTACT AND PRESSURE BETWEEN A STATIONARY AND REVOLVING BODY FOR ELECTRICAL MACHINES.

Application filed June 27, 1924. Serial No. 722,674.

This invention relates to a device for maintaining uniform contact and pressure between a stationary and revolving body for electrical machines.

5 One of the objects of the present invention is to provide an improved means whereby a predetermined and uniform pressure may be maintained between the contacting points of a stationary and a revolving body 10 in an electrical machine.

A further object of the invention is to provide a generally improved contact making body such as carbon brushes which prolongs the life of the same and thereby economizes in the number of replacements.

15 A further object of the invention is to provide an improved carbon brush holding device for electrical motors or generators and the like whereby the adjustment of the 20 carbon with respect to the armature may be readily made as wear insues on the carbon brush.

A still further object of the invention is to provide means for indicating the spring 25 pressure and adjusting the spring pressure on the carbon brush.

A still further object of the invention is to provide a substantially enclosed casing 30 for the carbon brush and thereby prevent accumulation of dirt and foreign particles on the sides of the brush which ordinarily interfere with the proper operation of the brush.

These and other objects are accomplished 35 by providing a construction and an arrangement of the various parts in the manner hereinafter described and particularly pointed out in the appended claims.

40 In the drawings, Fig. 1 is an end elevational view partly in section of a conventional form of generator showing the manner in which my improved carbon brush holder may be secured to any form of frame construction for properly supporting the carbon brush in operative relation with the armature.

Fig. 2 is a longitudinal cross sectional view of my improved carbon brush holder showing the relative position of the different 45 parts with respect to the casing.

50 Fig. 3 is an end elevational view of the casing of my improved carbon brush holder, and

Fig. 4 is a cross sectional view taken on the lines 4—4 in Fig. 2 and looking in the 55 direction indicated by the arrows.

One of the essential features of my invention is the provision of an improved means for maintaining proper contact so as to accomplish proper current connection 60 between the revolving armature and stationary brush holder of electrical machines. The invention in the present instance is particularly directed to carbon brushes as the medium of transmitting the current from 65 the revolving armature to the stationary member, but, it will, of course, be understood that other contacting mediums may be used and still be within the contemplation of my invention. Considerable difficulty has been experienced in connection with maintaining proper and uniform tension of the carbon brush which contacts with the revolving armature and considerable difficulty has also been experienced in 70 connection with the accumulation of dirt and foreign materials on the sides of the carbon brush interfering with the uniform flow of current from one body to the other.

To overcome these difficulties I have provided a brush holder in the form of a substantially enclosed casing 10 which is preferably provided with a longitudinally rectangular opening 11 which extends through the casing. The casing is preferably provided with a plurality of weight reduction 80 apertures 13 and a transversely extending rib 14, which is adapted to engage any convenient groove, as shown at 15, formed in the frame member 16 of the conventional 85 form of generator shown in Fig. 1. The casing is provided with apertures 17 arranged on the opposite sides thereof for the reception of bolts 18 for securing the brush holder or casing to the frame of the motor 90 or generator. Secured to the casing 10 by means of screws 19, which are in threaded engagement with the casing 10, as shown at 95 20, is a cap 21. The cap 21 is preferably provided with a recess as shown at 22, which is arranged around its perimeter for snugly seating the inner portion of the cap 21 into the upper end of the longitudinally extending aperture 11 of the casing 10. Slidably mounted in the longitudinally extending 100 aperture 11 of the casing 10 is a contact

105

making body or carbon brush 23, which is of substantially the same dimensions or slightly smaller than the size of the rectangular opening 11 in the casing. Positioned in contact with the inner end of the carbon brush 23 and positioned in the rectangular opening 11 of the casing 10 is a plate 24. The plate 24 is provided with, on its outer ends, cylindrical lugs 25, which are adapted to engage and support oppositely disposed compression springs 26. Formed integrally with the plate 24, at the center thereof, is a cylindrical boss 27 which is adapted to engage and support and retain in position a third compression spring 28. Secured to the boss 27 of the plate 24 in any preferred manner is a rod 29, which has a portion of its outer end threaded as shown at 30. Secured to the plate 24 between the springs 26 and 28 by means of rivets 31 are current shunts 32, which are preferably made of phosphor bronze. These shunts 32 have their ends bent upwardly and inclined outwardly, as shown at 33, with their extreme outer ends curved inwardly as shown at 34 to frictionally engage the inner walls of the casing 10. This construction permits these shunts to engage the sides of the wall under tension and to insure positive contact with the inner sides of the wall of the casing. Positioned in the rectangular opening 11 of the casing 10 adjacent the cap 21 is a spring pressure plate 35, which is adjustably mounted therein, and is provided with on its outer ends two cylindrical lugs 36, which correspond to the lugs 25 on the plate 24 and are in alignment therewith for retaining and supporting the compression springs 26 in position. The plate 35 is further provided with a central cylindrical lug or boss 37, which corresponds to the boss 27 and co-operates therewith for supporting and maintaining the spring 28 in its operative position. Extending through the boss 37 and plate 35 is a central bore 38, which slidably receives the rod 29.

When wear insues on the carbon brush 23 it becomes necessary to adjust the plate 24 and plate 35 with their associated springs, and in order to make this adjustment I have provided a threaded bolt 39 which is provided with the usual head 40. The bolt 39 is positioned centrally of the cap 21 and is in threaded engagement with a bore 41 in said cap. The lower end of the bolt is in contact with the outer surface of the plate 35, as shown at 42, and when it is necessary to adjust the carbon brush 23 by reason of wear on the brush in the longitudinal rectangular aperture 11 of the casing 10, the bolt 39 may be adjusted for accomplishing this purpose. In order to lock the bolt 39 in predetermined positions of adjustment I have provided a lock nut 43, which is in

threaded engagement with the bolt and is provided on one side thereof with a conical portion 44, which is adapted to engage an annular bevelled flange 45 formed integrally with the cap 21 adjacent the threaded aperture 41.

One of the essential features of my improved brush holding mechanism is the provision of means for maintaining a substantially uniform tension on the carbon brush up to the time the brush is completely worn down. This means comprises the providing of a longitudinal bore 46 in the bolt 39 which is adapted to reciprocally receive the rod 29. The rod 29 is provided with a nut 47 which is in threaded engagement with the threaded portion 30 of the rod and adapted to engage the upper side of the head 40 of the bolt 39 for effecting an adjustment and indicating the tension that is being exerted by the springs on the carbon brush 23. In order to lock the nut 47 in predetermined positions of adjustment I have provided a lock nut 48.

In the operation of my improved brush holding mechanism it will, of course, be understood that a definite spring tension must be exerted on the brush in accordance with the area of the brush in contact with the armature and that when this is determined the bolt 39 and the rod 29 are adjusted in such a manner as to exert the proper tension on the brush holder to insure the proper contacting pressure between a carbon brush and the armature. And when the brush holder and carbon brush are in their operative positions or in the position shown in Fig. 1 with the carbon contacting the armature the nut 47 will be slightly spaced, for example an eighth of an inch, from the outer end of the head 40 of the bolt 39 indicating that the springs 26 and 28 are under a predetermined pressure. This pressure, of course, is transmitted through the plate 24 to the carbon brush 23 and as wear insues on the brush the amount of wear on the carbon will be indicated by the reduction in the space between the nut 47 and the head 40 of the bolt 39. When this space is reduced from its predetermined setting of an eighth of an inch it indicates that in order to bring the carbon brush 23 under its previously set spring tension, and retain the spring under tension uniformly, it is necessary to loosen the lock nut 43 and adjust the bolt 39 inwardly of the casing to a point in which the space between the nut 47 and the head 40 of the bolt is the same as it was when it was originally set.

Of course, it will be understood that I have provided ample means whereby a wide range of varying spring tensions may be had, but in order to obtain the best results and eliminate unnecessary replacement of carbon brushes, previously determined

spring pressure that is best suitable for the type of carbon employed should be maintained throughout the life of the brush in order that the best results obtainable may 5 be had.

From the above description it will be readily seen that I have provided a very simple and efficient means whereby the spring tension on the carbon brush is indicated and additional means whereby the device may be adjusted to maintain uniform tension during the life of the carbon brush. It will also be noted that by positioning the carbon brush within substantially an 10 closed casing that the possibility of dirt or other foreign material accumulating on the sides of the brush and interfering with the efficient operation of the brush is eliminated.

As previously pointed out the spring pressure exerted on the carbon brush is indicated by the relative position of the nut 47 secured to the rod 29 with respect to the top of the head of the bolt 40. In other words, when the spring tension on the carbon brush has 20 been reduced by the wear thereon causing the plate 24 to move in a direction toward the armature and carrying the rod 29 with its nut 47 inwardly toward the casing and thereby reducing the space between the nut 25 47 and head 40 of the bolt 39, thereby indicating that the pressure of the springs has been reduced from what it has been previously set at.

It will be further noted that I have provided a construction by means of which the length of unused brush still available for service after the brush has been in use for some time may be indicated by the relative position of the head 40 of the bolt 39 with 30 respect to the top of the lock nut 43 together with the space between the head 40 of the bolt 39 and the nut 47 of the rod 29. By reason of this construction the greatest 35 service or life of the carbon brush is utilized 40 consistent with the efficient operation of the brush and thereby economizing in the number of replacements and indicates the time when such replacements should be made.

It will be further understood from the 45 above description that I have provided an improved form of carbon brush holder which substantially encases the whole carbon brush as well as the springs which resiliently press the carbon brush in contact 50 with the armature and that by positioning the springs so that they exert a force on the carbon brush in a direction parallel with the movement of the carbon brush as it is worn down by the armature the difficulty which 55 60 has been encountered by the old style of spring exerted brush in which the torsional spring is positioned on one side of the brush and exerting a diagonal force on the brush instead of a longitudinal pressure has been 65 overcome.

While in the above specification I have described one embodiment which my invention may assume in practice, it will, of course, be understood that the same is capable of modification and that modification 70 may be made without departing from the spirit and scope of my invention as expressed in the following claims.

What I claim as my invention and desire to secure by Letters Patent is:

1. In combination with an electrical machine of an armature therefor, a carbon brush holder comprising a casing adapted to be secured to said machine, said casing having an opening therein, a carbon brush 80 mounted in said opening and adapted to have one end in contacting relation with said armature, a plate mounted in said opening and engageable with the other end of said carbon brush, a second plate positioned 85 in said opening adjacent said first named plate, and a plurality of springs mounted between said plates for exerting pressure on said carbon brush.

2. In combination with an electrical machine of an armature therefor, a carbon brush holder comprising a casing adapted to be secured to said machine, said casing having an opening therein, a carbon brush mounted in said opening and adapted to have one end in contacting relation with said armature, a plate mounted in said opening and engageable with the other end of said carbon brush, a second plate positioned in 90 said opening adjacent said first named plate, a plurality of springs mounted between said plates for exerting pressure on said carbon brush, and means connected to said first named plate for indicating the spring pressure being exerted on said carbon brush. 100

3. In combination with an electrical machine of an armature therefor, a carbon brush holder comprising a casing adapted to be secured to said machine, said casing having an opening therein, a carbon brush 110 mounted in said opening and adapted to have one end in contacting relation with said armature, a plate mounted in said opening and engageable with the other end of said carbon brush, a second plate positioned 115 in said opening adjacent said first named plate, a plurality of springs mounted between said plates for exerting pressure on said carbon brush, means connected to said first named plate for indicating the spring pressure being exerted on said carbon brush, and means whereby said springs and second named plate may be adjusted to maintain uniform pressure on the carbon brush. 120

4. In combination with an electrical machine of an armature therefor, a carbon brush holder comprising a casing adapted to be secured in said machine, said casing having an opening therein, a carbon brush mounted in said opening and adapted to 125 130

have one end in contacting relation with said armature, a plate mounted in said opening and engageable with the other end of said carbon brush, a second plate positioned in 5 said opening adjacent said first named plate, a plurality of springs mounted between said plates for exerting pressure on said carbon brush, means connected to said first named plate for indicating the spring pressure being exerted on said carbon brush, and a bolt in threaded engagement with said casing and engageable with said second named plate whereby said spring and second named plate may be adjusted to maintain uniform 10 pressure on the carbon brush.

5. In combination with an electrical machine, of an armature therefor, a carbon brush holder comprising a casing adapted to be secured in said machine, said casing having an opening therein, a carbon brush mounted in said opening and adapted to have one end thereof in contacting relation with said armature, a plate mounted in said opening and engageable with the other end 20 of said carbon brush, a second plate mounted in said opening, springs mounted between said plates for exerting a resilient pressure 25 on said carbon brush, a bolt adjustably connected with said casing for regulating the tension of said springs, and a rod extending through said bolt and connected to said first named plate indicating the pressure exerted on said springs.

nected with said casing for regulating the tension of said springs, and means extending 30 through said bolt and connected to said first named plate indicating the pressure exerted on said springs.

6. In combination with an electrical machine, of an armature therefor, a carbon brush holder comprising a casing adapted to be secured in said machine, said casing having an opening therein, a carbon brush mounted in said opening and adapted to have one end thereof in contacting relation 40 with said armature, a plate mounted in said opening and engageable with the other end of said carbon brush, a second plate mounted in said opening, springs mounted between 45 said plates for exerting a resilient pressure on said carbon brush, a bolt adjustably connected with said casing for regulating the tension of said springs, and a rod extending through said bolt and connected to said first named plate indicating the pressure exerted 50 on said springs.

In testimony whereof I have signed my name to this specification, on this 23rd day of June A. D. 1924.

WILLIAM C. WHEELER.
